UNITED STATES PATENT OFFICE.

ISAAC BAAS, JR., AND LINN BOYD BENTON, OF MILWAUKEE, WISCONSIN,
ASSIGNORS TO BENTON WALDO & CO.

TYPE-MOLD.

SPECIFICATION forming part of Letters Patent No. 326,009, dated September 8, 1885.

Application filed May 19, 1884. (No model.)

To all whom it may concern:

Be it known that we, ISAAC BAAS, Jr., and LINN BOYD BENTON, of the city and county of Milwaukee, and State of Wisconsin, have 5 invented certain new and useful Improvements in Type-Molds; and we do hereby declare that the following is a full, clear, and exact description of the invention, which will enable others skilled in the art to which it pertains 10 to make and use the same, reference being had to the accompanying drawings, and to the letters of reference marked thereon, which form a part of this specification.

Our invention relates to molds employed in 15 type-casting machines.

It consists, essentially, of a lug or stop-block, which is attached to one segment of the mold so as to strike against the other segment and prevent the lateral spreading of the mold.

20 Its object is to avoid what are technically called by type-founders "swell-bodies."

In the accompanying drawings, like letters refer to the same parts in the several figures.

Figure 1 is a side elevation of a type-mold 25 to which our improvement is applied. Fig. 2 is a perspective view of the upper segment of the mold, exposing its inner face, and Fig. 3 is a like view of the lower segment, the former being turned up and the latter turned 30 down from the positions in which they are shown in Fig. 1.

A is the upper segment of the mold, and B the lower segment, which, relatively to the upper segment, is stationary.

35 C is the carriage of the upper segment, and C' the carriage of the lower segment. a is the end of the opening which forms the mold proper.

F is the register of the upper segment, and 40 F' the register of the lower segment, between which the matrix is placed when the mold is in operation.

As heretofore constructed a more rapid movement of the type-machine or a quicker 45 plunge of the pump by which the melted metal is forced into the mold, causing a greater pressure upon its walls, would force its sides a little farther apart, owing to a slight yielding or springing of the parts by which 50 said upper segment, C, is connected with the machine, thereby producing "swell-body

type," so called. The variation thus produced in a single type is too minute to be detected by the naked eye, but is readily distinguishable by the use of accurate measures 55 or gages, and when a number of such swell-body type are set in line this variation is multiplied and becomes marked and troublesome. In order to overcome this difficulty, we provide a stop-block, D, which is adjustably attached to the carriage C of the upper segment, A, and projects downwardly, so as to strike and bear against the end of the carriage C' of the lower segment, B, when the mold is closed.

In order to secure an accurate bearing between the stop-block D and the carriage C', the sides of the mold proper, a, are brought snugly together, and the right-hand ends of the carriages C C' are accurately faced down 70 together in a plane inclined to the bodywise dimension of the mold, as seen in the drawings. The face of the stop-block D, adjacent to the carriages C C', is accurately faced in a plane parallel with that of the ends of said carriages. A plate, E, of such thickness as to permit sufficient space between the sides of the opening at a, for casting type of the desired running-wise dimension, is inserted between the beveled end of carriage C and the 80 stop-block D, which is brought snugly up against the same by means of screws b, passing through said block and plate into carriage C. The beveled face of the stop-block D, attached to the beveled end of carriage C, 85 will therefore be parallel with the beveled end of carriage C', and when the segments A B of the mold are brought together will form a perfect bearing therewith. The beveled faces of the carriages C C' and of the stop-block D allow the upper segment of the mold to be obliquely lifted from the lower segment, in the usual way.

When the segments of the mold are brought together in readiness to receive the melted 95 metal between them, the face of the stop-block D bears against the end of the carriage C', thereby preventing the further spreading apart of the sides of the mold proper at a.

For casting bodies of different running-wise 100 dimensions, plates E of proportionate thickness are employed.

The stop-block D may be variously modified in form. Instead of beveling the ends of both carriages C C', we may face the end of carriage C in a perpendicular plane or parallel with the sides of the mold proper and make that portion of the face of stop-block D which rests against it or against the plate E to correspond therewith. We prefer, however, the construction first described. The location, also, of the stop-block D may be changed without departing from the principle of our invention. For instance, instead of attaching it directly to one of the segments of the mold, it may be attached to one of the mold-blocks, to which said mold-segments are rigidly secured when in use. The nearer, however, the block is placed to the opening at *a* the more effective will be its operation, since the unequal expansion and the greater springing of the parts by which each segment is connected with the machine is thereby avoided.

Having thus described our invention, what we claim as new, and desire to secure by Letters Patent, is—

1. The combination, with the segments which compose a type-mold, of a stop-block, D, substantially as and for the purposes set forth.

2. The combination of the carriages C C', of a type-mold having their ends beveled in parallel planes, and the beveled stop-block D, attached to the beveled end of carriage C, substantially as and for the purposes set forth.

3. The combination, with a type-mold, composed, as described, of two segments, A and B, of the carriages C C', stop-block D, adjustably attached to one of said carriages, and the plate E, inserted between block D and the carriage to which it is attached, substantially as and for the purposes set forth.

In testimony that we claim the foregoing as our own we affix our signatures in presence of two witnesses.

ISAAC BAAS, JR.
LINN BOYD BENTON.
